UNITED STATES PATENT OFFICE.

HARRY STITES, OF HARRISBURG, PENNSYLVANIA.

DESIGN FOR A BADGE.

SPECIFICATION forming part of Design No. 19,350, dated October 8, 1889.

Application filed June 28, 1889. Serial No. 315,942. Term of patent 3½ years.

To all whom it may concern:

Be it known that I, HARRY STITES, a citizen of the United States, residing at Harrisburg, county of Dauphin, and State of Pennsylvania, have invented and produced a new and original Design for a Badge, of which the following is a specification, reference being had to the accompanying drawing, forming part thereof.

10 The leading features of my design are two flags, drapery or scroll, book, with a square and compasses, arm and hammer, encircled by a shield, suspended from top bar or scroll, with star.

15 A A represent two flags; B, drapery or scrolls; C, book over part of flags; o, a badge of the Jr. O. U. A. M., composed of a square and compasses, arm and hammer, encircled by a shield, comprising the lower part of the badge, suspended from E, top bar or scroll, 20 with F, a star, on it.

I claim—

A design for a badge, consisting of two flags, drapery or scroll, book, top bar or scroll, with star, with a shield-shaped lower portion, as 25 shown and described.

HARRY STITES.
